SLIDING FLANGEWAY FILLER AND TAPERED FILLER BLOCK FOR RAILROAD CROSSINGS AND FROGS

Norman F. Higgs, P.O. Box 1642, Fresno, Calif.

Filed Apr. 11, 1956, Ser. No. 577,523

4 Claims. (Cl. 246—380)

My invention relates in general to a railway track crossing structure with the general purpose of providing flangeway fillers for the lines of rails of each trackway in order to provide continuous traction surfaces for the wheels in crossing over the flangeways and thus prevent jarring of the cars and destruction of the rails.

Another object of my invention is to provide flangeway fillers which will reduce the wear and breakage of wheels by eliminating large gaps between the ends of the rails.

A further important object of my invention is to facilitate and make possible the use of rubber surfacing of the wheels by eliminating the damage caused by the sudden jar or dropping at the rail separations in crossings and flangeways.

A further purpose of my invention is to provide a retractable device which may be attached to and operated by any of the standard types of signal controls and operating mechanisms.

A further purpose of my invention is to provide a sliding flangeway filler which contains an emergency safety means for holding together in working condition parts of the flangeway filler which may become broken or damaged.

A further object of my invention is to provide a sliding flangeway filler in which the strong and sturdy construction affords long life and also relatively inexpensive costs both for installation and operating maintenance.

Another purpose of my invention is to provide a tapered flangeway which is capable of adjustment when worn and may eventually be easily changed for the installation of a replacement.

A further purpose of my invention is to provide a tapered sliding flangeway filler which is efficient in operation and requires only a small amount of power to be placed in, to be withdrawn from, and to be retained in the operating position when the train wheels are passing over the crossing.

An important advantage of my device is that the tapered filler blocks wherein the flangeway fillers slide are simple in construction and easy to install in place of the standard filler blocks normally used.

A further advantage of my invention is that the bearing surfaces of the sliding parts may be lubricated by using the standard powdered graphite usually available in railway maintenance supplies.

An important object of my invention is to reduce as much as possible the annoying clicking of the wheels arising from passage over unsupported rail intersections.

A further object of my invention is to provide a smooth traction surface thus resulting in minimum vibration and maximum comfort to passengers.

A further object of my invention is to provide a tapered sliding flangeway filler and cooperating tapered filler block which may be readily constructed at minimum cost as compared to the standard railway crossing.

Another object is to provide a flangeway filler adapted for longitudinal slidable movement between spaced rails and between filling and retracted positions.

2

Additional objects and advantages will be apparent from the following description considered in conjunction with the accompanying sheet of drawings or from both as supplements of each other, wherein are set forth certain novel features of construction, combination and arrangements of parts and functions.

In the drawings:

Figure 1 is a plan view of a main line railway crossing showing an embodiment of my invention.

10 Figure 2 is a fragmentary somewhat enlarged section taken on the line 2—2 of Figure 1 including a wheel representation.

15 Figure 3 is a cross section taken on a plane at a position represented by line 3—3 of Figure 2, also including a wheel representation.

Figure 4 is a perspective of the flangeway filler.

15 Figure 5 is a partially sectional perspective of a tapered filler block.

20 Referring now in detail to Figures 1, 2, 3, 4 and 5, the numeral 6 indicates a railway crossing between intersecting tracks 7 and 8 with the assumed direction of travel shown by the arrow 9.

25 Main line rails 10, 11, 12 and 13 are connected or integrally formed with intersecting main line rails 14, 15, 16 and 17. A center integrally formed or connected guard rail section is indicated by numeral 18.

Guard rails 19, 20, 21, 22, 23, 24, 25 and 26 are connected with or integrally formed with main rails 27, 28, 29 and 30 to form flangeways 31, 32, 33, 34, 35, 36, 30 41, 42, 45, 46, 49, and 50. Within flangeways 35 and 36 are located a pair of retractable fillers 37 and 38 operating or sliding in the opposite direction to that of a pair of retractable fillers 39 and 40 slidably operating in flangeways 41 and 42.

35 A pair of retractable fillers 43 and 44 slidably operate in flangeways 45 and 46 in the opposite direction to a pair of retractable fillers 47 and 48 sliding in flangeways 49 and 50.

As illustrating the use of one type of operating mechanism, the retractable fillers 43 and 44 are connected to links 51 and 52 joined by a cross bar 53 to which is attached a pull rod 54. Similarly, retractable fillers 47 and 48 are connected to links 55 and 56 joined together by cross bar 57, to which is attached pull bar 58.

45 Pull bars 54 and 58 are connected to the track signal and control mechanism so as to be subject to operating forces tending simultaneously to separate them and to remove the retractable fillers 43, 44, 47 and 48 from the portions of the flangeways 45, 46, 49 and 50 nearest the crossing intersection.

50 To retractable fillers 37 and 38 are connected links 59 and 60 joined by a cross bar 61 to which is attached a pull rod 62. Similarly, retractable fillers 39 and 40 are connected to links 63 and 64 joined together by cross bar 55 65 to which is attached pull bar 66. Pull bars 62 and 66 are connected to the track signal and control mechanism so as to be subject to operating forces tending simultaneously to close them and to position the retractable fillers 37, 38, 39 and 40 in the portions of the flangeways 35, 36, 41 and 42 nearest the crossing intersection. It will be noted that the retractable fillers 37, 38, 39 and 40 are connected in pairs to the track signal and control mechanism in a special way so as to be in an alternate position with respect to the retractable fillers 43, 44, 47 and 48, whereby one set of the main line rails 10, 11, 12 and 13 or 14, 15, 16 and 17 at a time is in condition for passage of the train wheels, as 72.

55 The numeral 67 indicates a typical elongated tapered sliding filler, such as previously referred to by numerals 70 37, 38, 39, 40, 43, 44, 47, and 48, which in operated position has a top longitudinally extended bridging surface 68 adapted to be positioned flush with the top rail surface 69,

and a forward end surface 70 adapted to be positioned flush with the side edge 71 of the rail. The top surface 68 closely fits and contacts the traction surface of wheel 72, while the end surface 70 forms a barrier or stop for the wheel flange 73.

Tapered sliding filler 67 is provided for part of its length with a key 74, a bottom full length key section 75, and a concave slide contacting bottom surface 76. The bottom surface extends along a line in acute angular relation with the top bridging surface 68 so that the top and bottom surfaces taper or converge, but do not meet, toward the forward end surface 70. The keys define elongated grooves 67a on opposite sides of the filler extended longitudinally of the filler substantially parallel to the bottom surface. The keys 74 have upper substantially horizontal shoulders 74' outwardly extended relative to the top bridging surface.

Drilled lengthwise through the sliding filler 67 is a circular channel or bore 77 in which a wire rope 78 is securely positioned and tensioned by expanded ends 79 and 80 which are welded or otherwise tightly secured to the end surfaces 70 and 82. Spaced parallel connecting lugs 83 and 84 are fastened to the end 82 of the sliding filler 67. A pin 85 is inserted through apertures in the lugs, and an eye 86 of a pull rod 87 so as to connect the pull rod pivotally to the lugs.

Cooperating with sliding filler 67 is a tapered filler mounting block 88 tightly secured or wedged between main rail 89 and guard rail 90. In filler block 88 is formed an elongated, longitudinally extended U-shaped channel 91 having an open top, a concave rounded bottom surface 92 which is complementary to and forms a slide and bearing surface for the rounded bottom bearing surface 76 of sliding filler 67, and side walls upwardly extended from the bottom surface. Channel 91 is formed at a longitudinal angular inclination, with the shallowest channel depth located at a forward rail intersection end 93 and coinciding with a similar channel 94 formed in another intersecting filler block 95 identical with block 88. Ribs 96 and 97 are longitudinally extended along the inner surfaces of the side walls of the channel and are adapted complementarily to fit in the grooves 67a of the filler 67.

The rails 89 and 90 correspond to any laterally spaced pair of rails 10 through 17 and 19 through 30, shown in Fig. 1 which form the flangeways 31 through 36, 41, 42, 43, 46, 49, and 50. Each rail has horizontal upper and lower flanges 100 and 101, respectively, interconnected by a vertical web 102. The rails are positioned with their webs in spaced parallel relation and with their upper flanges edgewardly spaced and having their upper load bearing surfaces in a common horizontal plane, as best seen in Fig. 3.

In the utilization of my invention for its several purposes in railway intersections or frogs it is desirable to first replace the standard railway filler blocks with my tapered filler blocks, and subsequently insert each of the sliding fillers and connect the various sets of operating linkages to the appropriate sets of fillers. The connecting ends of the linkages may then be attached to the railway signal and control system, which will then function to close or retract the sliding fillers in accordance with the needs of the system as determined by the towerman or suitable automatic control devices.

More specifically, filler 67 is mounted for longitudinal slidable movement in the filler block 88 incident to pulling or pushing on the corresponding rods 54, 58, 62, and 66. The fillers are slidable between upper positions, as seen in Fig. 3, with their top bridging surfaces 68 fitted between and substantially coplanar with the upper surfaces of the upper flanges 100 of the laterally adjacent rails, as 89 and 90, and a retracted position with said top bridging surfaces below said rail flanges. Engagement of the shoulders 74' with the upper flanges 100 limits upward sliding movement of the filler and insures positioning of the bridging

surface 68 in a plane precisely coplanar with the load bearing surfaces of the upper flanges. Accordingly, the filler together with the upper flanges provide a continuous load bearing surface for the passage of a train wheel 72 thereover. However, in the retracted position of the filler, the upper surface 68 of the filler is positioned far enough below the upper load bearing surfaces of the flanges 100 so that wheel flange 73 does not contact the bridging surface 68.

It will be noted that although I have shown provisions for the operation of my sliding flangeway fillers by mechanical linkage control it is also contemplated that anyone of several wellknown standard railway mechanisms may be substituted. Suitable connections and adaptations can be readily selected to alter my device for operation by systems of electrical, hydraulic, pneumatic or mechanical signalling and power sources.

It will be understood that while the form of my sliding flangeway filler and tapered filler block for railroad crossings and frogs, herein illustrated and described, is to be considered as a preferred embodiment of my invention, I do not limit myself to the precise constructions as disclosed, but reserve the right to resort to and substitute various modifications and changes in shape, size and arrangement of parts without departing from the spirit of my invention or the scope of my claims as described and indicated above and in the drawings and the following claims.

Having thus described my invention, I claim:

- 30 1. In a device for use in providing a continuous support surface at railroad crossings in which elongated rails intersect and provide gaps therein at the points of intersection so that railway cars may traverse either of the rails, which rails provide upper surfaces disposed in a substantially common horizontal plane, the combination of an elongated mounting block mounted longitudinally along each rail and extended from the gap in its respective rail away from the other rail and in alignment with the gap in its said other rail, each mounting block providing an upwardly disposed inclined surface from its extended end toward the gap in its respective other rail, a filler member slidably mounted on each of the mounting blocks on said inclined surface thereof for reciprocal movement along an inclined rectilinear path between a position with the uppermost end thereof disposed in the gap of its respective other rail and a retracted position removed from the gap, means for moving the filler members alternately and oppositely between gap filling and retracted positions, and means on the filler members engaging their respective rails in said gap filling positions and limiting upward movement of such filler members to positions with their uppermost ends flush with the upper surfaces of their respective rails.
- 35 2. In the device of claim 1 wherein the rails have upper substantially horizontal flanges providing said upper surfaces of the rails, and wherein said means on the filler members includes shoulders outwardly extended from the filler members and engaging the flanges of their respective rails in said gap filling positions.
- 40 3. In the device of claim 1 wherein each mounting block has a substantially U-shaped channel therein extended longitudinally of the respective rail to which it is connected, wherein the inclined surface of each block constitutes a bottom surface for its respective channel,
- 45 4. In the device of claim 1 wherein each channel has side walls upwardly extended from its bottom surface and an open top opening upwardly through the gap in its said other rail, wherein elongated ribs are extended inwardly of each channel from the side walls thereof in longitudinally inclined relation substantially parallel to the bottom surface of their respective channel, and wherein each filler member has elongated side grooves slidably fitted on the ribs in its respective channel for guiding each filler member along its rectilinear path.
- 50 5. The combination of claim 1 wherein each filler

member has opposite ends spaced longitudinally of the respective rail to which it is connected, and wherein elongated tension members are individually extended longitudinally through the filler members and have opposite ends connected to the opposite ends of their respective filler members for resisting fragmentation of the filler members incident to fracture thereof.
